DESIGN FOR A CHILD'S ROCKER

Bernard Bellville, St. Louis, Mo.

Application April 12, 1946, Serial No. 128,550

Term of patent 7 years

(Cl. D34—15)

To all whom it may concern:

Be it known that I, Bernard Bellville, a citizen of the United States, residing in the city of St. Louis, in the State of Missouri, have invented a new, original, and ornamental Design for a Child's Rocker, of which the following is a specification, reference being had to the accompanying drawing, forming part thereof.

Figure 1 is a top plan view of a child's rocker showing my new design thereof;

Figure 2 is a side elevation of the same;
Figure 3 is a front elevation of the same;
Figure 4 is a rear elevation of the same; and
Figure 5 is a perspective view thereof.

I claim:

The ornamental design for a child's rocker, substantially as shown.

BERNARD BELLVILLE.
